UNITED STATES PATENT OFFICE.

GEORGE H. REYNOLDS, OF NEW YORK, N. Y., ASSIGNOR OF ONE-HALF TO
GEORGE H. ROBINSON, OF SAME PLACE.

SUBMARINE TORPEDO-BOAT.

SPECIFICATION forming part of Letters Patent No. 245,864, dated August 16, 1881.
Application filed June 11, 1878.

To all whom it may concern:

Be it known that I, GEORGE H. REYNOLDS, of the city, county, and State of New York, have invented certain new and useful Improvements in Torpedo-Vessels, also applicable in part to other vessels; and I do hereby declare that the following is a description of the same, reference being had to the accompanying drawings, which form part of this specification.

- 10 This invention is mainly designed to be applied to self-propelling controllable torpedo-vessels, and I shall here describe it accordingly, and as applied to a vessel of such description in which an electric current passed through an insulated-wire cable is used as the controlling-power; but the several parts, or certain of them, may be made to perform their various functions in vessels not employing electricity as the controlling-power.
- 15 One portion of the invention relates to the form or construction of the hull of a torpedo or submarine vessel; and in order to explain this part of the invention and its objects or advantages, I would observe that the vessel should be of such form that it is not liable to dive too deep under water, and, on the other hand, is not inclined to run too much above water. Supposing a vessel to be cigar-shaped aft and of approximately-horizontal shovel shape in front, then, although the vessel may be so ballasted that she will lie perfectly level and fair in the water when at rest, she will either run out or under water when running at a high speed, accordingly as her forward part is shaped to turn up or down. To obviate this and facilitate the steering, I construct the vessel with a cylindrical body having a stern of conical form and a bow of wedge or ax shape, with its converging sides vertical.
- 20 The invention also consists in the combination, with a submarine vessel, of sight or target rods hinged so that they may be adjusted into an approximately-horizontal position or swung into an upright position; also, in the combination, with the vessel and such adjustable sight or target rods, of an electric-circuit cable and mechanism which is controlled by a current of electricity for operating said rods.
- 25 Again, the invention consists, in a combination, with movable sight or target rods applied
- 30 to the vessel, of an actuating cylinder and piston and controlling liquid cylinder and piston for raising and lowering said rods and for limiting the rapidity of such action; and in this connection the invention furthermore consists in a combination, with rising and lowering target-rods at or near opposite ends of the vessel, of one or more connecting-rods for simultaneously operating said target-rods by one and the same means, and which preferably consists of an actuating-cylinder and its piston and controlling liquid cylinder and its piston, as in the case of the steering devices.
- 35 The invention also consists in the combination, with a submarine vessel, of two or more connected and simultaneously-operated side rudders on each side of the vessel, for directing the vessel upward and downward while keeping it in a horizontal position, and an actuating cylinder and piston for the operation of the said rudders simultaneously by means of compressed air or other fluid under pressure.
- 40 The invention also consists in various details of construction and combinations of parts to be hereinafter described.
- 45 In the accompanying drawings, Figure 1 represents a plan of a torpedo boat or vessel constructed in accordance with the invention. Fig. 2 is a vertical longitudinal section of the same, and Fig. 3 is a side view thereof. Figs. 4 and 5 are a plan and elevation, respectively, of the sight or target rod apparatus. Figs. 6 and 7 are a side elevation and longitudinal section, respectively, upon a larger scale, of certain portions of said target-rod apparatus.
- 50 Figs. 8, 9, and 10 are a plan, vertical longitudinal section, and transverse section, respectively, of the water-weighting and buoyancy compartments.
- 55 Referring in the first instance, or more particularly, to Figs. 1, 2, and 3 of the drawings, A is the body portion of the hull, which is preferably of cylindrical form, terminating in a cone, B, in the rear, and extended in front to connect with or form a bow, C, of wedge or ax shape construction, having its converging sides vertical. This construction of the hull has several advantages. Thus the cone-shaped aft enables the rear rudder, D, to change the course of the vessel in a lateral direction.

quickly, and the ax-shaped bow or forward portion prevents any tendency of the vessel to dive forward, and provides for the vessel remaining on the same even keel or level both when running and when at rest. The body A is made up in part of a flask or reservoir, E, which carries the motive or propelling agent. Said agent may be compressed air or a gas under a high state of compression. The body A has also within it, or is made up in part of, another chamber, F, Figs. 1, 8, 9, and 10, for reception of a cable, which serves the double purpose of holding the vessel in check and, by means of an insulated wire or wires within the cable, of establishing an electric communication between the torpedo-vessel and another ship or the shore, to control the movements of the torpedo. Said cable is packed in the form of a cylindrical coil within the chamber F, and is paid out from it as the boat or vessel advances. The chamber F is somewhat larger than is necessary for the cable, and I arrange in the upper part of it, above the cable, what may be termed a "buoyancy-chamber," G, for the following purpose. In all vessels of the class to which this belongs the weight of them so nearly equals their displacement that there is always a tendency for them to turn over in the water. The buoyancy-chamber G, which is simply an air-chamber, assists in obviating this. Thus holes b are made in the bottom of the cable-chamber F. These holes allow the water on the outside of the boat to pass freely in and out, and as the boat runs the cable by which the boat is held in check or made capable of recovery when at a distance, and by which the electrical current to control the movement of the boat or explosion of the charge is communicated, passes out from the center of the coil in the chamber F in an aftward direction through a pipe or tube, H. This action causes quite a rapid flow of water along with the cable out of the chamber F, and any air in the said chamber is gradually carried out with the water. But the air-light chamber G upon the cover, or in the upper part of the cable-chamber F, serves to buoy up the vessel and to prevent her turning over by reason of said chamber G having a fixed position in the upper part of the vessel.

The engine I, which drives the propeller J, is placed in a separate compartment, K, Fig. 2, and is allowed to be submerged by circulating water from the outside through said compartment, for the purpose of keeping the temperature of the engine-cylinder and its pipes and valves at all times above the freezing-point.

Pipes c d pass through the cable-chamber F, one, c, of which serves to connect the flask E with the propeller-engine I, and the other, d, of which is connected with the pump worked by the engine, and serves to keep up an increasing charge of water within the boat to compensate for the loss of weight by the use of the gas. The shaft of the propeller and its engine is made hollow, that it may serve as an

exhaust-pipe to the engine. Apart from the shaft of the propeller-engine being hollow, as and for the purpose described, said engine may be of the usual or any suitable construction. 70

The rudder D at the stern of the boat, for steering the latter laterally, may be of ordinary form; but the means for operating it are peculiar; but as these means are not a part of this invention, and may constitute the subject 75 of a separate application for Letters Patent, it is not necessary here to describe them.

S S, Figs. 1, 2, and 3 of the drawings, are side deflecting-rudders for directing the course of the vessel up and down. There may be two 80 or more of these rudders on each side of the vessel; but only two are represented, placed near the ends thereof and connected by rods t t, as shown in Figs. 1 and 3. The whole of these rudders are connected together and are operated simultaneously by means of a piston in an air or gas cylinder, M', (see Fig. 2,) which is supplied with compressed air or gas from the reservoir or flask E, the piston-rod of said piston being shown near the right-hand end 85 of Fig. 2 as furnished for this purpose with a rack, r, which gears with a toothed sector, S, on the shaft, which is common to the two side rudders, which are arranged near one end of the boat. The said piston is connected with 90 a piston in another cylinder, P', which I term a "controlling-cylinder," by which the movements of the said rudders are controlled, and by which they are locked in any desired position; but as I intend to make this controlling 95 cylinder and piston and their appurtenances the subject of a separate application for patent, no further description of them is here necessary. The connection and gearing of the said side rudders are such that all are kept at the 100 same angle to the horizon, and as they are arranged near the ends of the vessel they will, when set at any angle to the center line of the vessel, all have a uniform tendency to produce the descent or ascent of each end of the vessel, and so cause the latter to rise and fall in such manner as to keep it longitudinally in a 105 horizontal position in the water at all times.

T T are the sight or target rods, to which are attached the targets V V for indicating 110 above the water the position and direction of the vessel when the latter is submerged. These rods are hinged to the top of the vessel at a suitable distance apart, and are connected by connecting-rods U to insure their simultaneous action. When down they lie close to the top of the vessel. They are raised to a vertical or any other desirable position by means of a toothed sector, S', (see Figs. 2 and 5,) provided on one of them, and a rack, r', attached 115 to the piston-rod of a piston working in an actuating-cylinder, M'', which is supplied with compressed air or gas from the reservoir or flask E, and which is furnished with a suitable valve for the induction and excretion of the 120 air and gas from said cylinder. This valve is controlled by an electric current through the 125

above-described cable. The said piston is also connected with a piston working in what may be called a "controlling cylinder," P^2 , (see Figs. 5, 6, and 7,) which is filled with any suitable incompressible liquid, and between whose ends there is communication by an outside passage, n , in which is placed a screw or other stop or valve, q , by which to contract the passage at one point for the purpose of more or less checking the passage of the liquid from one end of the cylinder to the other, and thereby more or less retarding the movement of its piston, and so regulating the velocity of the piston of the actuating-cylinder M^2 , and thereby controlling the movement of the targets.

Instead of the outside passage, N , on the controlling-cylinder P^2 , there might be a passage through the piston of said cylinder.

What I claim as my invention, and desire to secure by Letters Patent, is—

1. A submarine vessel having its hull constructed of a cylindrical body, terminating at its one end in a conical stem and at its other end in a vertical-sided and vertical-edged wedge or ax shaped bow, substantially as specified.

2. The combination, with a submarine vessel, of sight or target rods hinged so that they may be adjusted into an approximately horizontal position or swung into an upright position, substantially as specified.

3. The combination, with adjustable sight or target rods applied to the vessel, of an actuating cylinder and piston, and controlling liquid cylinder and piston for raising and lowering said rods and for limiting the rapidity of their action, essentially as described.

4. The combination, with rising and lowering target-rods at or near opposite ends of the vessel, of one or more connecting-rods for simultaneously operating said target-rods by one and the same means or actuating devices applied to one of said rods, substantially as specified.

5. The combination, with a submarine vessel, of adjustable sight or target rods, an electric-circuit cable, and mechanism actuated by an electric current through said cable for operating said rods, substantially as specified. 45

6. The combination, with a submarine vessel, of an adjustable sight or target rod, a toothed sector attached thereto, an operating cylinder and piston, and a rack upon the piston-rod engaging with said sector, substantially as specified. 50

7. The combination, with a submarine vessel, of adjustable sight or target rods, a cylinder and a piston to be operated by air or gas for adjusting said rods, a valve controlling the admission of air or gas to said cylinder, and an electric cable through which said valve is operated, substantially as specified. 55

8. The combination, with a submarine vessel, of adjustable sight or guide rods connected together by a connecting-rod, a toothed sector attached to one of said rods, an operating cylinder and piston, a rack upon the piston-rod engaging with said sector, and a valve operated by electricity for controlling the operation of said piston, substantially as specified. 65

9. The combination, with a submarine vessel, of two or more side rudders on each side thereof, all connected to be operated simultaneously and set at corresponding angles of inclination, and an actuating cylinder or piston for operating the same, substantially as and for the purpose herein set forth. 75

10. The combination, with a submarine vessel, of two or more side rudders on each side thereof, a connecting-rod connecting the rudders upon each side to give uniform motion thereto, and an operating cylinder and piston controlled by the electric current for actuating said rudders, substantially as specified. 80
